Patented June 17, 1975

235,466

FINGER RING

George Volkhausen, 79 Albert Ave.,
Cranston, R.I. 02905

Filed Oct. 25, 1973, Ser. No. 409,642

Term of patent 14 years

Int. Cl. D11—01

U.S. Cl. D45—10 A

FIG. 1

FIG. 2

FIG. 3

FIG. 4

FIG. 5

FIG. 1 is a front elevational view of a finger ring showing my new design;

FIG. 2 is a rear elevational view thereof;

FIG. 3 is a side elevational view thereof;

FIG. 4 is a top plan view thereof; and

FIG. 5 is a bottom plan view thereof.

The drawing is schematically shaded for contrasting color.

I claim.

The ornamental design for a finger ring, substantially as shown and described.
